UNITED STATES PATENT OFFICE.

FRED A. DENNETT, OF SHEBOYGAN, WISCONSIN.

DESIGN FOR A VENEER-PRESSING MEMBER.

SPECIFICATION forming part of Design No. 33,966, dated January 22, 1901.

Application filed December 7, 1900. Serial No. 39,103. Term of patent 14 years.

To all whom it may concern:

Be it known that I, FRED A. DENNETT, a citizen of the United States of America, residing at Sheboygan, in the county of Sheboygan and State of Wisconsin, have invented and produced a certain new, useful, and original Design for an Article of Manufacture—to wit, a Veneer-Pressing Member—of which the following is a specification, reference being had to the accompanying drawings, forming a part thereof.

In said drawings, Figure 1 is a plan view of a veneer-pressing member embodying my design. Figs. 2 and 3 are views in cross-section of the same, taken on lines 2 2 and 3 3, respectively, in Fig. 1. Figs. 4 and 5 are longitudinal sectional views taken on lines 4 4 and 5 5, respectively, in Fig. 1, these five views being deemed necessary for full illustration.

The leading and essential feature of my design for a veneer-pressing member consists of the peculiar and novel formation of all the portion of the surface of the same which is raised above the plane of the border herein-after described.

The surface shown in Fig. 1 between the points *a*, *b*, *c*, and *d* is rectangular in form, and aside from the raised portion before referred to is in one plane. The rear edge of the raised portion between the points *ff* takes the form of a semicircle, and from each point *f* to the points *e* each edge of the raised portion proceeds on a straight line parallel with the sides *a c* and *b d*. The edge of the raised portion between the points *e e* is indefinite, but substantially straight and parallel with the side *c d*. The slopes of the raised portion from the semicircular edge *f* and the straight

lines *e f* rise rather abruptly, as shown in the sectional view, Figs. 2 and 3. From the center of the forward end of the raised portion a valley or depression proceeds back toward the semicircular line and gradually rises to the highest level of said raised portion on an irregularly-curved surface, as shown at *g* in Fig. 4, slightly in the rear of the straight line taken between the points *f f*. The sides of said valley or depression slope in either direction with curved surfaces toward the raised portions. (Shown in Fig. 3.) From an indefinite straight line between the points *e e*, aside from the portion taken up by said depression, the slopes of the raised portion proceed from said indefinite line *e e* to the highest portion of said raised portion more gradually than the slopes from the semicircular edge and the edges *e f*.

The several minor features of my design of a veneer-pressing member may be stated as follows: The top of said veneer-pressing member is flat and its plane is parallel with the planes of the lower surface of said member, aside from the raised portion. The sides are parallel planes and stand at right angles with the upper surface, as do the ends.

Having thus described my design, what I claim is—

The design of a veneer-pressing member, substantially as shown and described.

Signed by me at Milwaukee, Wisconsin, this 22d day of November, A. D. 1900.

FRED A. DENNETT.
